CONVERTIBLE SOFA BED

David E. Waddell, Clearwater, Fla., assignor to Cass Manufacturing Co., Inc., Tampa, Fla., a corporation of Florida

Filed Mar. 25, 1960, Ser. No. 59,878

Term of patent 14 years

(Cl. D15—11)

Fig. 6

Fig. 1 is a perspective view of a convertible sofa bed in seating position showing my new design;

Fig. 2 is a top plan view of the same;

Fig. 3 is a side elevational view of the same;

Fig. 4 is a perspective view showing the article in its extended position;

Fig. 5 is a side elevational view thereof; and

Fig. 6 is a rear elevational view in seating position.

I claim:

The ornamental design for a convertible sofa bed, as shown.
